DESIGN FOR A GLASS BOTTLE

Lawrence J. Kihm, Pittsburgh, Pa., assignor to
J. T. & A. Hamilton Company, a corporation
of Pennsylvania

Application March 18, 1937, Serial No. 68,269

Term of patent 7 years

To all whom it may concern:

Be it known that I, Lawrence J. Kihm, a citizen of the United States, residing in Pittsburgh, in the county of Allegheny and State of Pennsylvania, have invented a new, original, and ornamental Design for a Glass Bottle, of which the following is a specification, reference being had to the accompanying drawing, forming part thereof.

In the drawing: Fig. I is both a front and rear elevation of a glass bottle showing my new design; Fig. II is a side elevation of the glass bottle; and Fig. III is a fragmentary vertical section through the wall of the glass bottle, taken on the section line III—III of Fig. II.

The design is characterized by the vertically disposed bands of lozenge-shaped decorations applied to the four corners of the bottle body for approximately the height thereof in the manner shown, the bands extending from the corners partially around the narrow ends of the bottle to provide marginal spaced rows of ornamentation on said end portions, while the front and rear faces of the bottle are smooth and unornamented except for the spaced corner decorations at each marginal border line of said face portions.

I claim:

The ornamental design for a glass bottle, substantially as shown and described.

LAWRENCE J. KIHN.
